[57] CLAIM

The ornamental design for a baby walker's seat cover, as shown and described.

DESCRIPTION

FIG. 1 is a front perspective view of a baby walker's seat cover showing our new design;

FIG. 2 is a front elevational view thereof;

FIG. 3 is a rear elevational view thereof;

FIG. 4 is a left side elevational view thereof, the right side elevational view being a mirror image of that shown;

FIG. 5 is a top plan view thereof;

FIG. 6 is a bottom plan view thereof; and

FIG. 7 is a front perspective view thereof installed on a baby walker's seat, the broken lines are for illustrative purposes only and form no part of the claimed design.

*FIG. 5**FIG. 6**FIG. 7*
